UNITED STATES PATENT OFFICE.

PHILIP MUHR, OF PHILADELPHIA, PENNSYLVANIA.

DESIGN FOR A SILVERSMITH'S STOCK OR ORNAMENT.

SPECIFICATION forming part of Design No. 25,769, dated July 14, 1896.

Application filed May 23, 1896. Serial No. 592,883. Term of patent 3½ years.

To all whom it may concern:

Be it known that I, PHILIP MUHR, a citizen of the United States, residing in the city and county of Philadelphia, State of Pennsylvania, have invented and produced a new and original Design for Silversmiths' and Jewelers' Ornaments, of which the following is a specification, reference being had to the accompanying drawing, showing a part thereof.

10 The leading feature of my design for an ornament for silversmiths' and jewelers' use is a foliated stem or stalk, the leaves being arranged in wave form.

The drawing represents a face view of an ornament embodying my design. 15

A designates a stem or stalk, and B designates a number of leaves thereon, said leaves extending in wave form on said stalk, and having pointed or forked ends.

What I claim is—

The design for an ornament, substantially as described and shown.

PHILIP MUHR.
